UNITED STATES PATENT OFFICE.

OTTO ZECH, OF DETROIT, MICHIGAN, ASSIGNOR OF ONE-HALF TO GUSTAV A. WINEMANN, OF SAME PLACE.

COMMUTATOR FOR ELECTRIC GENERATORS.

SPECIFICATION forming part of Letters Patent No. 389,184, dated September 4, 1888.

Application filed September 6, 1887. Serial No. 248,940. (No model.)

To all whom it may concern:

Be it known that I, OTTO ZECH, a citizen of the United States, residing at Detroit, in the county of Wayne and State of Michigan, 5 have invented certain new and useful Improvements in Commutators, of which the following is a specification, reference being had therein to the accompanying drawings.

This invention consists in certain new and 10 useful improvements in constructing commutators; and the invention consists in the mechanical proceeding and in its ultimate result in a finished commutator, all as more fully hereinafter described.

15 In the drawings, Figure 1 is a perspective view of the cylindrical insulating-body from which the commutator is formed. Fig. 2 is a similar view showing the body provided with a series of holes for the reception of the commutator-plates and the shaft. Fig. 3 is a 20 perspective view of one of the blanks, from which the commutator bars or plates are formed. Fig. 4 is an end view showing the commutator-blanks secured in the insulated body. Fig. 5 is a side elevation of Fig. 4. 25 Fig. 6 is a side elevation of the commutator in its finished condition. Fig. 7 is a cross-section on line $x-x$ in Fig. 6.

Figs. 1, 2, 4, 5, and 6 illustrate the successive steps taken in the manufacture of the commutator.

To begin with, a suitable insulating-body, A, of cylindrical shape and desired size, is prepared. This is then provided with a series 35 of holes, a , parallel to its axis and concentric thereto, the operation being best performed by the use of a templet to mark all the holes for drilling at once, the aperture b for the shaft being preferably drilled at the same time. 40 Commutator-blanks c of the description shown in Fig. 3 are then driven into the holes a , flush with one end of the commutator-body. These blanks are cut from phosphor-bronze, copper, or other suitable wire or round bar of 45 such length to reach through the insulating-body and project some distance at one end when secured in place. I preferably use wire or bar provided (in drawing it through the die) with a little feather or key, d , so that

when secured in place it is firmly held against 50 turning on its axis. Figs. 4 and 5 show the commutator at this stage of its manufacture. The next step in the operation is to turn off the face of the body of the insulator, and continuing such operation until the commutator-bars are sufficiently cut away to form the desired contact-surface between the outer ends, 55 e , left standing. Preferably this cutting away both of the insulating-body and the metallic bars is carried on until a little more than one- 60 half of said bars remain embedded in the remaining body of the insulator. If desired, in large commutators several rings may be left standing around the face of the commutator. The next steps of electrically connecting the 65 commutator and securing it in place are done in the ordinary manner, and do not form a subject of my invention. It only includes the steps heretofore described.

It will be easily understood that this way of 70 manufacturing the commutator has many advantages over the usual way of constructing such commutators, and wherein always great difficulty has been encountered in securing the plates so firmly as to prevent them from 75 becoming loose under the action of the brushes. In my construction nothing short of the breaking of the commutator can possibly detach the commutator-strips; and not alone this, but the process of manufacturing 80 is so extremely simple that on this score alone my invention is eminently economical and simple. As the commutator-plates cannot spring in turning, the result is absolutely perfect.

85 What I claim as my invention is—

1. A commutator composed of a single cylinder of insulating material and provided with collars integrally formed therewith, and of a series of metal rods provided with feathers or 90 keys and secured in a corresponding series of longitudinal perforations formed in the commutator, and the collars, substantially as described.

2. A commutator composed of a single cylinder of insulating material and having two collars integrally formed therewith, and of a series of metal rods secured in a correspond-
